(57) **CLAIM**

The ornamental design for a piping tip holder, as shown.

DESCRIPTION

FIG. 1 is a front elevation view of a piping tip holder showing our new design;

FIG. 2 is a rear elevation view thereof;

FIG. 3 is a top view thereof;

FIG. 4 is a bottom view thereof;

FIG. 5 is a right side view thereof, the left view being identical; and,

FIG. 6 is a front perspective view thereof.

The broken lines depict portions of the piping tip holder that form no part of the claimed design.
